UNITED STATES PATENT OFFICE.

GUSTAV E. FRITZ, OF CHICAGO, ILLINOIS, ASSIGNOR TO THE UNIVERSAL INTER-
CHANGEABLE TOOTH CO., OF PEORIA, ILLINOIS, A CORPORATION OF ILLINOIS.

READY-MADE ADAPTABLE BACKING FOR TEETH.

1,173,106.

Specification of Letters Patent. Patented Feb. 22, 1916.

Application filed June 8, 1914. Serial No. 843,683.

To all whom it may concern:

Be it known that I, GUSTAV E. FRITZ, a citizen of the United States, a resident of Chicago, in the county of Cook and State 5 of Illinois, have invented new and useful Improvements in Ready-Made Adaptable Backing for Teeth, of which the following is a specification.

This invention has reference to a new and 10 improved article of manufacture, being a ready-made adaptable backing for porcelain teeth, such as molars, bicuspids and facings.

The article comprises a backing forming a chair for the facing or tooth, bent into 15 form from a suitable piece of metal and having a retention post or pin attached thereto, preferably being soldered or welded.

Figure 1 shows opposite views, in perspective, of one form of backing; Fig. 2 shows 20 opposite views, in perspective, of another form of backing, and Fig. 3 shows opposite views in perspective, of still a further form of backing.

Like characters of reference denote corresponding parts throughout the figures.

Referring particularly to Figs. 1 and 2, the article comprises essentially a backing 25 in the form of a chair 1, same being bent into form from a suitable piece of metal and having the part 2 which lies against the posterior face or surface of a tooth; the opposite side walls or parts 3 adapted to engage or lie against the approximal surfaces of a tooth; the flange or part 4 to engage or lie 30 against the gingival margin of a tooth, and the flange or part 5, similar to the flange or part 4, to engage or lie against the occlusal surface of a tooth.

The portions 3, 4 and 5 of the chair are 35 continuations, one of another and are integral with the part 2. The part 2 may have the shapes shown in Figs. 1 and 2, or the necessary shape to conform to the tooth to which they are adapted, as will be under-

stood by those skilled in the art to which 45 the articles pertain.

6 denotes a retention post or pin. These posts or pins have a part 7 to be inserted into a tooth, to which the backing is attached, and of course will be of a shape to 50 conform to the opening in the teeth. Each post or pin 6 has a projection 8 which passes through an opening in the part 2 of the backing and soldered or welded thereto, so as to produce a firm connection between the 55 same and retain the post or pin 6 fixed relative to the backing to aid in interchangeability of the backing to teeth of the same kind.

In Fig. 3 the backing 1, does not have the 60 opposite side walls or parts 3, and in place of the part 4, has a bent portion 9 to form a protecting tip for the incisal edge of the tooth, and instead of the part 5 has a bent portion 10 to conform to the cervical border 65 of the tooth.

What I claim is:—

An article of manufacture, comprising a metallic backing for a tooth or facing, said backing being bent into form from a single 70 sheet of metal and having a portion adapted to lie against the posterior face of a tooth; opposite side portions of approximately triangular shape, adapted to lie against the approximal surfaces of the tooth; a bent 75 over portion at one end of the backing merging smoothly into said opposite side portions, adapted to lie against the gingival margin of the tooth, and a similar bent over portion at the other end of the backing 80 merging smoothly into said opposite side portions, adapted to lie against the occlusal surface of the tooth and a post or pin attached to said backing.

GUSTAV E. FRITZ.
